UNITED STATES PATENT OFFICE.

EDUARD SCHWERIN, OF BERLIN, GERMANY.

GAS BRACKET, PENDANT, AND THE LIKE.

No. 882,970.

Specification of Letters Patent. Patented March 24, 1908.

Application filed September 24, 1906. Serial No. 336,012.

To all whom it may concern:

Be it known that I, EDUARD SCHWERIN, manufacturer, a subject of the King of Prussia, German Emperor, and residing No. 118 5 Alexandrinien street, Berlin, in the Kingdom of Prussia, German Empire, have invented new and useful Improvements in and Connected with Gas Brackets, Pendants, and the Like, of which the following is a specification.

10 This invention relates to an arrangement of standard or pendent incandescent gas-lights for show or advertising purposes, which are set in rotation by wind wheels, spring mechanisms or the like.

15 The improvement consists in the combination of a revolvably mounted and rotating gas- and air-mixing tube, which bears incandescent lamps, with a fixed gas- and air-mixing nozzle, which extends into the mentioned 20 rotating mixing tube.

The invention is shown in the accompanying drawings, in which

Figure 1 is a side view partially in section of a lyre-shaped form of construction; Fig. 2 is a detail in sectional view and on a larger scale, showing a clockwork-mechanism of well known construction inclosed in a casing; and Fig. 3 is a cross-section along the line A—A of Fig. 2 and shows the ratchets, partially in section, and pawls for stopping the clockwork-spring.

The lyre-shaped frame has below an upright nozzle *a* which has above a short tubular attachment. Over this attachment, the 35 mixing pipe *b* of the incandescent gaslight burner is freely but yet tight-fittingly placed. The mixing tube *b* is connected with the usual burners *c*, and the whole is suspended by means of a rigid or elastic connecting 40 piece *e* from a clockwork mechanism arranged in a casing *d*, which is attached to the upper part of the lyre frame. The position as regards height of the burner is such, that the mixing tube does not rest firmly on the 45 nozzle *a* but is loosely held thereon in such a way as not to oppose too great a frictional resistance to the rotation.

The clockwork which operates the rotation of the burner is of well known construction, 50 consisting of watch-spring *g*, the one end of

which is connected with a shaft *h* and the other end with a casing *i* which is loosely mounted upon this shaft and provided with a sprocket-wheel *k* and with a pinion *l*. To the shaft *h* is fixed a second sprocket-wheel *m* 55 with which a pawl *n* meshes for stopping the movement of the shaft in one direction. A second pawl *o* is arranged for stopping the casing *i* when the shaft *h* is revolved for winding up the watch-spring. The pinion *l* 60 causes the gear *p* to revolve with the shaft *e*. A spring *q* is inserted between the wall of the casing *d* and the pinion *l* and acts to retard the revolving movement of the pinion *l* and of the gear *p* by producing a more or less 65 slight frictional resistance.

As is evident from the foregoing, the invention may be applied without further difficulty either to a standard or to a pendent incandescent gaslight apparatus, it being immaterial whether the latter has only one or several burners. The mounting which forms the object of the present invention may be also applied to the burners in the case of crown lights, wall brackets, table lamps and 70 the like without the means necessary for producing the revolvability causing any difficulties in the arrangement.

Having now described my invention, what I wish to secure by Letters Patent of the 80 United States, is:

In a carrier for gas incandescent lamps, the combination of a suspended clock-work; a mixing-tube suspended from said clock-work and carried and adapted to be rotated by the same; a plurality of gas incandescent 85 lamps attached to and being uniformly distributed around said mixing tube; a stationary gas-nozzle taking into the lower end of the mixing-tube, and a rigid frame supporting said gas-nozzle and connecting it with the suspended clock-work so as to keep the parts in their proper relative position and distance, for the purpose as described.

In witness whereof I have hereunto set my hand in presence of two witnesses. 95

EDUARD SCHWERIN.
